UNITED STATES PATENT OFFICE.

LEWIS E. DICKINSON, OF BOONTON, NEW JERSEY, ASSIGNOR TO WESTERN ELECTRIC COMPANY, INCORPORATED, OF NEW YORK, N. Y., A CORPORATION OF NEW YORK.

HEAT-COIL PROTECTIVE DEVICE FOR ELECTRIC CIRCUITS.

1,273,158.

Specification of Letters Patent. Patented July 23, 1918.

Continuation of application Serial No. 49,228, filed September 17, 1915. This application filed July 14, 1917. Serial No. 180,607.

To all whom it may concern:

Be it known that I, LEWIS E. DICKINSON, a citizen of the United States, residing at Boonton, in the county of Morris and State 5 of New Jersey, have invented certain new and useful Improvements in Heat-Coil Protective Devices for Electric Circuits, of which the following is a full, clear, concise, and exact description.

10 This invention relates to heat coil protective devices for electric circuits and has for its object the provision of an improved heating element which effects the functioning of said devices.

15 In accordance with this invention there is provided a heat coil in which the heat producing element through which the current passes is composed of a material having a high positive temperature coefficient as dis-

20 tinguished from the comparatively low temperature coefficients characteristic of resistance wires commonly used for heating purposes. This property, combined with that of high specific resistance common in resist- 25 ance wires for heating purposes makes it possible to employ a heat producing element which is economical in space and has a low resistance at normal temperatures but which increases rapidly in resistance with increase

30 in temperature due to the passage of the current, such increase in resistance in turn causing more heat to be generated. This cycle continues until sufficient heat has been generated to effect the release of a member held 35 in position by some easily fusible substance which permits the heat coil to perform its function.

This application is a continuation of my copending application Serial No. 49,228, filed Sept. 17, 1915.

In the drawing Figure 1 is a sectional view of a heat coil embodying this invention and Fig. 2 is an end elevation of the heat coil shown in Fig. 1.

45 In the drawing there is shown a heat coil provided with a shell (1) of a non-conducting material, such as bakelite, having one of its ends closed by a portion integral with the body portion thereof and the closed end 50 provided with a metallic cap 2. A pin 3 has one of its ends threaded to engage suitable threads formed centrally in the inside of the closed end of shell 1. A tube 4, pref-

erably made of copper and having a diameter greater than that of pin 3, is slipped over said pin and held in a given position with respect thereto by means of heat softenable material 5, such as low fusing solder. Wound upon the tube 4 is a coil of heat 55 producing wire 6 having one of its ends attached to said tube, the other end thereof being led out through a slit formed in the shell 1 and secured to the cap 2. At the point where the wire 6 is fastened to the 60 cap there is formed an indentation or recess, which serves as a protection for the leading-out portion of said wire. Both the pin 3 and the tube 4 project beyond the end of the coil 6, the pin itself extending beyond 65 the tube.

It may be mentioned here that the ideal winding for use as a heating element in a heat coil should possess a low resistance at 70 normal temperatures and at the same time be capable of producing sufficient heat under the action of abnormal currents to effect 75 the functioning of the heat coil. A winding composed of a material having a high positive temperature coefficient fulfills these 80 requirements and may be made from an alloy consisting of a large percentage of nickel. Such material, and one which has been found to be particularly suitable for this 85 purpose, is an alloy consisting of approximately 70% nickel and 30% iron. This material has a positive temperature coefficient of approximately .0038 per degree centigrade and a specific resistance of fifteen 90 microhms per centimeter cube, thereby making it possible to use a very efficient winding and one that occupies but little space. Other alloys having a temperature coefficient somewhat lower than the one mentioned above 95 were found to give a decided improvement over the materials commonly used heretofore. For example, the use of a material having temperature coefficient of .0018 per degree centigrade (approximately six times that of the German silver wire used at present) results in a gain in efficiency which permits a reduction of approximately 15% in the resistance of the coil. Since the 100 winding of the heat coil is connected directly in series with the line, a decrease in resistance of this magnitude is of great importance especially in the case of long and

105

expensive toll lines and it represents a decided improvement in the manufacture of heat coils.

As the method of inserting coils of the type in question in a protector strip is well known in the art, being illustrated, for example, in Patent 1,057,126 of March 25, 1913, to A. F. Dixon and Patent 944,540 of December 28, 1909, to W. L. Coursen, it is thought to be unnecessary to illustrate the method in the present case. In service the heat coil is under spring pressure and in case the solder is softened by abnormal currents in the windings 6, relative movement is permitted between the pin 3 and the tube 4, allowing said pin to project farther through the tube and in so doing to ground the line in the well known manner, as illustrated by the patents hereinbefore referred to. As a result of the low resistance of the winding at normal temperatures it will be apparent that comparatively little energy is consumed under normal conditions by the heat coil contemplated by this invention. However, due to the fact that the material of the winding has a high positive temperature coefficient, this decrease in energy consumption under normal conditions is not obtained at a sacrifice in operating efficiency of the heat coil under conditions of abnormal current.

What is claimed is:

1. A protective device for telephone circuits comprising a metal sleeve, a pin passing through said sleeve to which it is secured

by a heat softenable material, and a heating element composed of an alloy containing more than 50% nickel surrounding a portion of said sleeve.

2. A protective device for telephone circuits comprising a metal sleeve, a pin passing through said sleeve to which it is secured by a heat softenable material, a heating element composed of an alloy consisting of substantially 70% nickel and 30% iron surrounding a portion of said sleeve. 40 45

3. A protective device for telephone circuits comprising a metal sleeve, a pin passing through said sleeve to which it is secured by a heat softenable material, and a heating element surrounding a portion of said sleeve and composed of a nickel alloy having a positive temperature coefficient of more than .0018 per degree centigrade adapted to be connected in the circuit. 50 55

4. A protective device for telephone circuits comprising a metal sleeve, a pin passing through said sleeve to which it is secured by a heat softenable material, and a heating element surrounding a portion of said sleeve and composed of a material having a positive temperature coefficient of more than .0018 per degree centigrade and a specific resistance of more than ten microhms per centimeter cube at zero degrees centigrade adapted to be connected in the circuit. 60 65

In witness whereof I hereunto subscribe my name this 12th day of July, A. D. 1917.

LEWIS E. DICKINSON.
